UNITED STATES PATENT OFFICE.

HERMANN THEIS, OF OHLIGS, GERMANY.

BULLET-PROOF SUBSTANCE.

SPECIFICATION forming part of Letters Patent No. 678,064, dated July 9, 1901.

Application filed August 29, 1899. Serial No. 728,973. (No model.)

To all whom it may concern:

Be it known that I, HERMANN THEIS, director, of Ohligs, Germany, have invented a certain new and useful Improvement in Bullet-Proof Substances; and I do hereby declare the nature of this invention and in what manner the same is to be performed to be particularly described and ascertained in and by the following statement.

10 In the development of offensive and defensive armaments the fact is obvious that with the improvement in weapons of offense ways and means have been found of constructing defensive apparatuses in such a 15 manner that they are capable of resistance proportionately to the penetrating power of the shot.

The endeavor to make defensive armor so strong that it successfully offers the greatest 20 resistance to the force of the shot is most clearly shown in the history of modern armored defense.

For some time armor has been made which forms a great advance in the improvements 25 in means of protection. From the original wrought-iron plates laid over each other we have progressed to homogeneously-united composite armor-plates of wrought-iron, hardened steel, and nickel-steel facing; but 30 the efforts with all these armors have been to produce a homogeneous mass, the material of which was essentially steel and wrought-iron, and was designed to prevent projectiles penetrating through the armor-plates. It was es- 35 pecially endeavored to cause the shot to explode upon the hardened surface, and thereby render it harmless, because experience showed that when the shell penetrated the plate the action of the explosive substance 40 contained in the shell would destroy the armor. The deeper the shot penetrated into the plate the more the armor protection would be endangered.

The development of modern armor shows 45 by experience that defensive means cannot go beyond certain limits. The reasons for this are too long to be explained here, and it need only be mentioned that the iron industry has had to be slowly and progressively de- 50 veloped in order to cope with the requirements of defensive armaments. Artillery is in a more favorable position, inasmuch as the

penetration of the projectiles has been already considerably increased by means of the more efficient smokeless powder. It follows 55 from this that the limit of the efficiency of armor is closely dependent on the development of the iron industry, and it has been made the subject of much experiment lately to replace the hitherto customary use of steel 60 and iron for armoring by some other material. It can, however, be stated without exaggeration that no homogeneous material exists or can be made which surpasses iron or steel plates in resisting power. All efforts to 65 replace these by homogeneous or other manufactured material have hitherto failed.

The object of the present invention has been produced on a fundamentally-different principle. I have laid down three principles 70 which are entirely contrary to all armor known up to now, namely: First, the substance is not homogeneous, but is composed of parts of different degrees of resistance to the action of projectiles; second, the shot is to penetrate 75 into the substance and be retained therein, and, third, the energy in the shot is at the same time to be the cause of the destruction of the projectile itself. These principles have been realized by me by the manufacture of a 80 substance which actually affords the desired protection against projectiles.

I have primarily endeavored in the new shot-proof substance to counteract the effect 85 of the modern infantry-rifles of the newest construction, and this object has been attained in a surprising manner with the help of the bullet-proof substance described below. The steel-cased bullet of the modern infantry-rifle, which has been propelled by 90 the largest possible charge of powder, is in the substance itself burst into small pieces and firmly held there. This hitherto unheard of result has been attained by careful observation and experiment. It has been 95 discovered, namely, that if a projectile penetrates into a substance composed of various heterogeneous parts, in which each separate part of the substance possesses a different degree of resistance to the penetration of the projectile, and in which a portion of the mass possesses a relatively high resisting power, the penetrating projectile is destroyed and torn by means of the energy and the force of

rotation innate in the projectile. This discovery led to the invention of the bullet-proof material.

An example of this bullet-proof substance is illustrated in the accompanying drawings, in which—

Figures 1 and 2 are transverse sections through a portion of an armor, Fig. 1 showing on the left-hand end a soft backing, in which fragments of projectiles are embedded, and Fig. 2 showing on the right-hand end a metal plate for arresting fragments. Fig. 3 is an enlarged sectional detail view showing one method of attaching the metallic portions of the armor to the backing-plate.

a denotes fine steel blades about 0.6 millimeters thick and thirty millimeters wide. The strips *b*, embodying the conventional representation of chain-threads and weft of a fabric, are of woven material which are soaked in rubber solution and firmly joined to the steel blades under hydraulic pressure. As can be plainly seen from the drawings, the steel blades do not penetrate through the whole section of the substance, but only as far as the center of the whole material. By this arrangement of the blades the steel blades and the strips of material so follow on each other that at least three steel blades occupy a space which corresponds to the thickness of a projectile. This arrangement is especially calculated for infantry-bullets, for which this construction has been primarily designed.

The method of operation of this substance so constructed is as follows: The projectile striking against the surface indicated by the right-hand edge of Fig. 1 or by the left-hand edge of Fig. 2 penetrates into the substance and finds a different resistance in the steel blades as compared with that of the strips of woven material. The striking of the projectile against the few (two or three) sharp edges of the steel blades causes its shape to be altered, and by means of its own rotary motion and the energy of the projectile it is completely destroyed. It is divided into pieces and small particles, which are driven into the backing of the substance, as according to experiment the projectile penetrates into the substance half the width of the steel blades before it is destroyed completely.

That part of the substance which, as shown in the drawings, merely consists of strips of woven material is only intended to receive the burst particles of the bullet. This part of the substance, which is to serve as a protection against the particles of the burst projectile, can obviously be replaced by another construction. For example, it can be a strong steel plate *c* of one to one and one-half millimeters, which would serve as the backing of the target, Fig. 2. This above-described method of operation of the bullet-proof substance has been tested by careful experiments, in which the latest military infantry-

rifle, with the largest charge of powder, was employed, and in which the bullet was shot at ten meters distance from the target.

What has been said above with regard to the bullet-proof substance and also the drawings relates to a plate which has been tested against the action of infantry-rifles. The principle on which the plate has been manufactured can naturally in principle be used for armor-plating in general. Certainly in the manufacture of this kind of armor-plates the bullet-proof substance can be practically employed.

Through the successful operation of this new construction of armor-plating it is obvious that the present invention is of the greatest possible importance in the construction of defensive armaments.

There is still a special form of construction which perhaps might be used for heavy armor—for instance, armor-plates in war vessels, in breastworks for coast defenses, and the like. The inserted steel blades, corresponding to the size and power of penetration of large projectiles of heavy artillery, are constructed of steel bars of considerable thickness, and these are strongly connected to each other at the back by means of a cross-beam. (See Fig. 3.) It is advisable to entirely dispense with the intermediate strips between the steel blades, which, as above described, consisted of woven material, and not to fill up these spaces with substances of any kind.

What I claim, and desire to secure by Letters Patent of the United States, is—

1. A shot-proof armor composed of a plurality of materials offering different degrees of resistance to the penetration of a projectile, adjoining on lines substantially parallel to the direction of the shot or lying perpendicular to the surface of impingement and jointly forming said surface, whereby the projectile, by simultaneous impingement upon a plurality of layers having different degrees of penetration resistance, is retarded and laterally deflected, and disintegration thereof caused to result from the penetration, so that the momentum is substantially neutralized and the divided particles are retained in the mass.

2. A shot-proof armor made up of metallic and woven materials adjoining in planes substantially parallel to the direction of the shot to be withstood, and of dimensions sufficiently reduced to cause a plurality of layers to be impinged simultaneously by the shot, for the purpose herein set forth.

In testimony that I claim the foregoing as my invention I have signed my name in presence of two subscribing witnesses.

HERMANN THEIS.
